United States Patent Office

Des. 186,704
Patented Nov. 17, 1959

186,704

PORTRABLE OVEN

Archie M. Schwieso, Portland, Oreg.

Application June 30, 1958, Serial No. 51,587

Term of patent 3½ years

(Cl. D81—20)

Figures 3 and 4 are end elevational views of the oven taken from the left and right, respectively, of Figure 1; and

I claim:

The ornamental design for a portable oven, as shown.
